SCAFFOLD

Leo A. Reiner, Detroit, Mich.

Application June 20, 1939, Serial No. 280,146

5 Claims. (Cl. 304—2)

This invention relates in general to scaffolds and tower structures.

One of the objects of my invention is to provide a new and improved tower or scaffold structure which will be strong and durable.

Another object of the invention is to provide a tower or scaffold structure which may be quickly and conveniently erected.

A further object of the invention is to provide 10 a structure of the above mentioned character, parts of which may be readily and quickly replaced if necessary.

Other objects of the invention will become apparent from the following description taken 15 in connection with the accompanying drawings in which—

Figure 1 is a side view in elevation of my scaffold or tower structure;

Fig. 2 is a view shown in cross section of the 20 structure taken along the line 2—2 of Fig. 1;

Fig. 3 is a detail top plan view of part of the structure;

Fig. 4 is a vertical elevational view of the structure of Fig. 3;

Fig. 5 is an end view of the structure;

Fig. 6 is a sectional view taken along the line 6—6 of Fig. 5, and

Fig. 7 is a sectional view taken along the line 7—7 of Fig. 5.

30 Referring to the drawings by characters of reference, the scaffold or tower structure includes a pair of spaced unitary end structures each of which comprises, spaced, upright posts 10, an intermediate upright post 11, horizontal upper and lower cross members 12 and corner members 13. To provide for strength and rigidity the posts 10, 11 and cross members 12 are tubular in shape and the intermediate post is preferably welded at its upper and lower ends 35 respectively to the upper and lower tubular cross members 12.

The corner members 13 may be cast and each comprises a vertical tubular portion provided intermediate its upper and lower ends with integral, right angle tubular portions 14 and 16. As shown in Figs. 2 and 6, the corner pieces 13 telescopically receive end portions of the posts 10 and end portions of the cross members 12, the cross members 12 being received in the tubular portions 15 and the posts 10 being received in the vertical tubular portions of the corner members 13. Preferably, the corner members 13 are provided with internal shoulders, as shown, providing seats for the upper ends of the tubular posts and cross members, the lower ends of the

posts being provided with external shoulders 10b to seat on the upper ends of the lower corner members.

Angularly disposed tie rods 16, of which there are four, in the present instance, are provided for each end structure to rigidly secure the posts 10, cross members 12 and corner members 13 together. These tie rods 16 are secured at their inner ends as at 18a, to an anchor member which comprises a pair of clamping plates 17 which are 10 bent to fit against the post 11 and are tightly drawn together and secured to the post 11 by bolts and nuts 18. Preferably the tie rods 16, at their outer ends, have threaded connections with individual turnbuckles 20 which are secured respectively to webs 21 formed integral of the corner members 13. It will be seen that by tightening down the turnbuckles 20 that the corner members 13 will be urged toward each other and toward the common anchor plates 17, thus rigidly securing together the parts of respective end sections. These end sections may be constructed at the factory and conveyed as unitary structures to the location where the scaffold or tower or similar structure is to be erected.

As shown in Fig. 1, the above described end sections are spaced apart by upper and lower horizontal cross members 22, similar to the cross members 12 and these upper and lower cross members have their opposite ends received in 30 the other or tubular portions 16 of the corner members. Tie rods 23 are connected, as at 27, to webs 24 of diagonal corner members 13 having threaded connections with turnbuckles 25 which may be readily tightened down to rigidly 35 secure the parts together. Preferably, the lower corner members 13 have reduced lower end portions providing an external shoulder to seat on tubular bases or feet 26 to provide a more steady structure.

40 Mounted on the above described structure is a duplicate structure including lower corner members 13a which are provided with lower end reduced portions 27a which telescope into the upper ends of the corner members 13a and have external shoulders 27b to seat thereon; the corner members 13a also having horizontal tubular portions 14a to receive end portions of tubular cross members 12a. The end sections of the upper structures are provided with tie rods 16a to secure the parts rigidly together. It will thus be seen that the structure may be added to and built up to the desired height to provide a strong scaffold or a tower for an elevator for building construction work. In order to provide a rigid 50 55

sectionally constructed tower of the character above described, I draw the corner members 10a down tightly to the corner members 10 by vertical tie rods 28 and turnbuckles 29 at each corner of the structure. Adjacent their upper and lower ends, the tubular corner members 13, 13a are preferably slotted as at 30 and surrounding these tubular portions are clamping bands 32 for tightly clamping the slotted tubular portions 10 to their respective vertical posts. These clamping bands 32 have laterally extending spaced flanges 33 which are drawn together by bolts 34 and these bolts also secure the tie rods 28 and the turnbuckles 29 to the flanges. Thus by 15 tightening down the turnbuckles 29 it will be seen that successive sections of the structure may be rigidly secured together.

If now instead of building the structure upwardly or if in addition to building upwardly it is desired to build outwardly or laterally it will be seen that additional end sections may be readily set up on the ground alongside of and adjacent to the other lower section or sections and all of the laterally positioned sections may be rigidly tied together by tie rods. To this end, I prefer to use the structure shown in Figs. 3 and 4 as this permits of the use of common posts 36 for adjacent end sections. The corner members 13b are each provided with a single right angle tubular portion 14b to receive ends of the horizontal cross members 22. Adjacent their upper and lower end, the tubular portions 14b are preferably slotted and these portions are tightly clamped around and to the posts 10 by 30 clamping brackets 31, drawn together by nuts and bolts 38. These nuts and bolts 38 also serve to secure ends of the tie rods 23 to the corner members 13b thus providing common posts between adjacent end sections of the structure.

40 To erect the structure, if the end sections are built up or assembled at the factory, it is only necessary to set up the end sections in spaced relation, insert the connecting cross members 22 in their respective sockets or tubular portions of the corner members 13 and attach and 45 tighten the tie rods 23 by the turnbuckle 25. From the foregoing description it will now be seen that I have provided a new and improved scaffold or tower structure which may be quickly erected and one which is strong and rigid. In 50 addition to the time saved in erecting the present scaffold or tower structure, the parts thereof may be very inexpensively manufactured. Furthermore by reason of its construction and manner in which the parts go together, any of the 55 parts such as turnbuckles, tie rods, corner members, etc., may be readily replaced if necessary.

While I have shown and described my invention in detail it is to be understood that the same is to be limited only by the appended claims for 60 many changes may be made without departing from the spirit and scope of the invention.

What I claim is:

1. In a structure of the character described, a pair of spaced upright tubular posts, a pair of spaced tubular cross members connected to said posts, an intermediate upright post rigidly secured to said cross members, tubular corner

members having sockets receiving end portions of said pair of posts and having other sockets receiving end portions of said cross members, an anchor plate rigidly secured to said intermediate post, and tie rods individually securing said corner members to said anchor plate. 5

2. In a structure of the character described, upright tubular posts, upper and lower tubular cross members connected to said posts, corner members having sockets to receive end portions 10 of said posts and having other sockets to receive end portions of respective cross members, angularly disposed tie rods urging said corner members toward each other and rigidly securing said corner members, posts and cross members together, and a centrally disposed anchor plate to which the inner ends of the tie rods are secured. 15

3. In a structure of the character described, an upright tubular post, a tubular connecting member telescoping with an upper end portion 20 of said post, a second tubular connecting member seating on and telescoping with said first-named connecting member, an upright tubular post telescoping with said second-named connecting member, clamping means for clamping 25 said first-named connecting member and said first-named post together, second clamping means for clamping said second-named connecting member and said second-named post together, and means connecting said clamping 30 means together and urging said connecting members toward each other.

4. In a structure of the character described, an upright tubular post, a tubular connecting member having one end telescoping with the 35 upper end of said post, a second tubular member seating on and telescoping with the upper end of said first-named tubular connecting member, a second tubular post telescoping with the upper end of said second-named tubular connecting member, releasable clamping means tightly clamping said second-named connecting member to said first-named post, second releasable clamping means tightly clamping said first-named connecting member to said first-named post, and a turnbuckle connecting said 45 clamping means and drawing said second-named connecting member down against said first-named connecting member.

5. In a structure of the character described, 50 an upright tubular post, a tubular connecting member having one end telescoping with the upper end of said post, a second tubular connecting member seating on and telescoping with the upper end of said first-named connecting 55 member, a second tubular post telescoping with the upper end of said second-named connecting member, releasable clamping means tightly clamping said second-named connecting member to said second-named post, second releasable 60 clamping means tightly clamping said first-named connecting member to said first-named post, and means connecting said first-named clamping means and said second-named clamping means together and holding said second-named connecting member down against said first-named connecting member.

LEO A. REINER.
